COMBINED HANGER ARM AND BRACKET FOR USE WITH PERFORATED PANELS

Richard Dale Barnes, Rockford, Ill., assignor to
Southern Imperial, Inc., Rockford, Ill.

Filed July 15, 1974, Ser. No. 488,724

Term of patent 14 years

Int. Cl. D8—08

U.S. Cl. D8—255

FIG. 1 is a perspective view of a combined hanger arm and bracket for use with perforated panels incorporating my new design.

FIG. 2 is a top plan view.

FIG. 3 is a side elevational view.

FIG. 4 is a front elevational view as seen from the right of FIG. 1.

FIG. 5 is a rear elevational view as seen from the left of FIG. 1.

FIG. 6 is a fragmentary cross-sectional view taken along the line 6—6 of FIG. 1.

I claim:

The ornamental design for a combined hanger arm and bracket for use with perforated panels, as shown.
